LADY'S UNDERWEAR

Dorothy Gershen, Cleveland, Ohio

Application June 20, 1932, Serial No. 618,214

1 Claim. (Cl. 2-71)

This invention relates to improvements in ladies' underwear, and aims to provide a simple form of composite garment to replace a plurality of garments now commonly worn.

5 Other objects of the invention are to provide such underwear which is light and comfortable, and yet keeps the body fully covered at all times, and which can be quickly put on or taken off.

A further object of the invention is to provide 10 such underwear which is simple to make and easy to wash and iron.

With these and other objects and advantages in view which will become apparent as the specification proceeds, the invention is hereinafter more 15 fully described with the aid of the accompanying drawing, in which:

Figure 1 illustrates a front view of the garment showing a portion thereof torn away, and

Figure 2 is a partial rear view thereof.

20 Referring to the drawing, 1 designates my garment which consists essentially in four attached portions, namely a brassière 2, a girdle 3, pants 4 and an underskirt 5.

The brassière 2 is provided with conventional 25 shoulder straps 6 and is split from the top down one side as shown at 7.

The adjacent edges of this split portion are held together by means of suitable fastenings such as the cooperating fastener portions 8 and 30 8a. In order to render this portion of the garment form fitting darts 9 are provided.

A seam 12 is formed around the lower margin 35 of the brassière 2 to which the upper margin of the girdle 3 is sewn. This seam is form fitting so that portions of the garment cannot ride up on the person and become misplaced. The girdle 3 is also shaped to conform to the curvature 40 of the figure around the waist line and also to afford support for the abdomen. The girdle is also split at 7a to form a downward continuation of the brassière split 7, and the adjacent edges of the split portion are provided with cooperating fastener portions 10 and 10a similar to the fastener portions 8 and 8a.

45 A lower seam is formed around the lower margin of the girdle to which both the upper margin of the pants 4 and the underskirt 5 are sewn. This lower seam is also intended to cling to the figure to further assist in holding all the portions of the garment in their desired positions.

50 The upper portions of the pant legs are closed at 4a, and the lower outer portions are open at 4b, though suitable fasteners 4d may be provided thereon if desired. The inner sides of the legs 55 and the crotch are closed as shown at 4c preferably by a seam.

The underskirt 5, which covers the pants 4, may be of any suitable length and width to suit the wearer, and may be shaped to conform to the 60 width or style of the dress or skirt under which

it is to be worn. The underskirt is also preferably split downward a short distance from its upper margin to form a continuation of the girdle split 7a, and adjacent the margins of this split portion 7b cooperating fastener portions 11 and 11a are provided.

From the foregoing it will be noted that while the garment is all one, a single thickness of material can cover all portions of the body except that covered also by the pants; support both for 70 the bust and abdomen is provided, and the seams 12 and 12a which are form fitting assist in holding the various parts of the garment in their respective positions; and the closed crotch of the pants further assists in accomplishing the same 75 purpose. Thus it will be seen that even in the event of the shoulder straps breaking there is no danger of the garment slipping down and coming off.

While the pants 4 have been shown as shorts 80 their length may be varied to suit the desire of the wearer, or, if desired, the garment may be made without the pants, and the form fitting upper portions, namely the brassière 2 and the girdle 3, as well as the seams 12 and 12a will retain the 85 garment portions in place.

Though the preferred embodiment of the invention has been described and shown, it is understood that alterations and modifications may be made therein provided they fall within the 90 scope of the appended claim.

What I claim is:

A composite garment comprising a brassière portion, shoulder straps thereon, a girdle portion, the whole of the upper margin of which is permanently secured to the whole lower margin of 95 said brassière portion, an underskirt portion, secured to the lower margin of said girdle, a pants portion also secured to the lower margin of said girdle along the same line as said underskirt so 100 as to hang freely within said underskirt portion, said pants portion having a closed crotch and longitudinal slits formed in the lower portion of the legs, and said brassière portion, girdle portion and the upper part of the underskirt portion and 105 pants being longitudinally slit, fastening means on the opposite margins of said slit, and the girdle being so shaped as to afford support to that portion of the body which it covers, and covering said portion of the body with a single thickness of material only, said girdle portion flaring in width 110 both upwardly and downwardly from the side portions to the central portion, thus having its uppermost point located adjacent the intersection of the busts of a wearer.
